[57] CLAIM

The ornamental design for a tape-cassette box, as shown
and described.

DESCRIPTION

FIG. 1 is a top front perspective view of a tape cassette
box showing my new design;

FIG. 2 is an inverted bottom rear perspective view
thereof;

FIG. 3 is a front elevational view;

FIG. 4 is a rear elevational view;

FIG. 5 is a top plan view;

FIG. 6 is a bottom plan view; and

FIG. 7 is a left side elevational view, the right side
elevational view being identical thereto.

FIG. 1

FIG. 2

FIG. 4

FIG. 5

FIG. 3

FIG. 7

FIG. 6
